DESIGN FOR A BROOM HOLDER OR SIMILAR ARTICLE

John Newton Payne, Pembroke, Ky.

Application May 8, 1940, Serial No. 92,224

Term of patent 14 years

To all whom it may concern:

Be it known that I, John Newton Payne, a citizen of the United States of America, residing at Pembroke, in the county of Christian, State of Kentucky, have invented a new, original, and ornamental Design for a Broom Holder or Similar Article, of which the following is a specification, reference being had to the accompanying drawing, forming a part thereof.

Figure 1 is a front perspective view of a broom holder showing my new design. Figure 2 is a side elevational view of the said broom holder, the other side of the aforesaid broom holder being substantially the same as the side shown.

I claim:

The ornamental design for a broom holder or similar article, as shown and described.

JOHN NEWTON PAYNE.
